Primary Examiner — Darlington Ly(74) *Attorney, Agent, or Firm* — Christopher A. Proskey; BrownWinick Law Firm(57) **CLAIM**

The ornamental design for a shelf pin hole jig having a plurality of guide channels, as is shown and described.

DESCRIPTION

FIG. 1 is a top, front, and left side perspective view of a shelf pin hole jig showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a top, rear, and right side perspective view thereof with the guide accessory exploded apart.

The broken lines in the drawings illustrate portions of the shelf pin hole jig that form no part of the claimed design.

1 Claim, 6 Drawing Sheets(56)
